DESIGN FOR A FOUNTAIN PEN

Irving Florman, New York, N. Y.

Application March 15, 1946, Serial No. 127,532

Term of patent 14 years

(Cl. D74—17)

To all whom it may concern:

Be it known that I, Irving Florman, a citizen of the United States, residing in the city of New York, county of New York, and State of New York, have invented a new, original, and ornamental Design for Fountain Pens, of which the following is a specification, reference being had to the accompanying drawing, forming a part thereof in which the single figure is a view in side elevation of a fountain pen showing my new design.

I claim as my invention:

The ornamental design for a fountain pen, as shown.

IRVING FLORMAN.
